(57) **CLAIM**

The ornamental design for a lightweight closure with complete top spokes, as shown and described.

DESCRIPTION

FIG. 1 is an isometric view of a lightweight closure with complete top spokes according to our new design.

FIG. 2 is a top view of the lightweight closure with complete top spokes of FIG. 1.

FIG. 3 is a bottom view of the lightweight closure with complete top spokes of FIG. 1; and,

FIG. 4 is a right side view of the lightweight closure with complete top spokes of FIG. 1; the left side, front view and back view are all mirror images.

The portions of the drawings appearing in broken lines are for environment only and do not form a part of the claimed design.
